ATTORNEY

UNITED STATES PATENT OFFICE.

ALVIN B. HENDRICKS, OF ST. MARY'S, ILLINOIS.

REGULATING-SOCKET FOR INCANDESCENT LAMPS.

SPECIFICATION forming part of Letters Patent No. 553,911, dated February 4, 1896.

Application filed June 19, 1895. Serial No. 553,384. (No model.)

To all whom it may concern:

Be it known that I, ALVIN B. HENDRICKS, a citizen of the United States, residing at St. Mary's, in the county of Hancock and State of Illinois, have invented certain new and useful Improvements in Regulating-Sockets for Incandescent Lamps; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates generally to an improvement in rheostats, but more particularly to regulating-sockets for incandescent and other electric lamps.

The object of the invention is to regulate 20 the intensity of an incandescent electric lamp by providing a device by means of which the amount of resistance thrown into or out of a circuit, and consequently the intensity of the lamp or lamps in the circuit, may be varied 25 at will.

The invention relates to the particular form of mechanism by means of which this end is accomplished.

In the accompanying drawings, Figure 1 is 30 a side view of the device complete. Fig. 2 is a view of the interior operating parts, the side of the casing being removed. Fig. 3 is a detail end view of one of the resistance-spools. Fig. 4 is a side view of the hub to 35 which the radially-extending spindle is secured at its inner end, and Fig. 5 is a plan view of one of the insulating-disks which are interposed between the spool of the resistance-wire and the contact-button at the outer 40 end thereof.

Like letters of reference in the several figures of the drawings refer to identical parts.

The letter A indicates the casing, which may be of any desired size. The preferred 45 form, as shown in the drawings, is disk-shaped. Piercing the casing centrally and transversely is the shaft B, provided with the crank-handle C for convenience in turning. Secured upon the shaft within the casing is a block or 50 hub D, of fiber or other insulating material, having faces corresponding with the number

of resistance-coils to be used. In the drawings eight coils, made preferably of German silver, are shown secured one upon each face, but the number may vary as circumstances 55 require.

The coils or spools E E' are each mounted upon a radially-extending spindle F, secured at one end in the hub and suitably insulated so that it will have no contact with the resistance-wire which is wound around it. Caps or contact-plates G, preferably of copper, serve to hold the coils upon the spindles. A sheet of mica, fiber, or other insulator g is interposed between the wire of each coil and 60 its contact-plates, so that the end of the wire of each coil piercing the insulating-sheet has electrical connection with its contact-plate at but one point g', as shown in Fig. 5 of the drawings. Opposite coils are connected through 65 the hub D, as shown in Fig. 2.

The line-wires H H' enter through the dome a and the positive wire H is suitably connected with the spring-finger I, secured at one end to the casing, from which it is insulated 70 by the block i. The fingers are so arranged that their free ends make contact with the contact-plates of opposite coils at opposite points, so that the current entering on the positive wire H passes through the finger I, 75 the adjacent coil E, the connecting-wire J, the coil E', the finger I', and into the lamp, passing out directly through the negative conductor H'. A suitable socket K is secured to the casing to receive the stem of the lamp. 80

Opposite coils are preferably, though not necessarily, of the same, or substantially the same, resistance, but each opposite pair varies from the others in the amount of resistance it offers, from which it will be readily seen that 85 by operating the crank-handle to introduce the different pairs of coils into the circuit any desired amount of resistance may be had, and as any number of coils may be used it will be possible to vary the power of the lamp within 90 wide limits.

Having thus described my invention, I claim as new and desire to secure by Letters Patent—

1. The herein-described regulator for electric lamps consisting of a socket to receive the lamps, a hub provided with radially-extend-

ing coils of varying resistances, and stationary contact-fingers arranged to close the circuit successively through the resistance-coils as they are revolved.

5 2. The herein-described regulator for electric lamps, &c., consisting of a casing provided with a socket to receive the lamp, a hub journaled within the casing, radially-extending resistance-coils, stationary contact-fingers
10 arranged to close the circuit when brought into contact with the resistance-coils by the revolution of the hub, substantially as described.

15 3. The herein-described regulator for electric lamps, &c., consisting of a casing provided with a socket to receive the lamp, a revoluble hub journaled within the casing radially-extending spindles secured to the hub, resistance-coils secured upon the spindles, contact-plates in electrical connection with the coils, and stationary contact-fingers
20 arranged to close the circuit through one or

more of the resistance-coils, substantially as described.

4. The herein-described regulator for electric lamps consisting of a casing provided with a socket to receive the lamp, a revoluble hub of insulating material journaled within the casing, a series of radially-extending spindles secured to the hub, resistance-coils arranged upon the spindles, contact-plates also secured upon the spindles but insulated therefrom and in electrical connection with the respective coils, and stationary contact-fingers arranged within the casing to close the circuit
30 successively through the coils as the hub is revolved substantially as described.

In testimony whereof I affix my signature in presence of two witnesses.

ALVIN B. HENDRICKS.
